LOADING AND WRAPPING MEANS

Charles H. Petskeyes, Davenport, Iowa, and Israel C. Gellman, Rock Island, Ill., assignors to Gellman Manufacturing Company, Rock Island, Ill., a corporation of Illinois

Application February 27, 1939, Serial No. 258,673

12 Claims. (Cl. 93—2)

This invention has as its principal object the provision of article loading and initial wrapping mechanism for use in wrapping machines of general application and particularly bread wrapping machines.

5 In one of its novel aspects the invention provides a reciprocable loading table arranged for cooperation with a vertically reciprocable article carrier or elevator in such manner that an article on the table will be automatically transferred onto the elevator when the latter is in a particular position.

10 In another of its novel aspects, the invention provides initial folding or wrapping means which includes a vertically reciprocable elevator arranged to coact with other wrapping instrumentalities and a horizontally reciprocable article loading table arranged for coaction with the elevator and with paper feeding means so that when 15 the elevator is in lowered position a sheet of wrapping paper will be suspended or draped across the path of an article moving onto the elevator, and such article will be transferred automatically from the table into the paper and 20 onto the elevator to effect a partial enfoldment of the wrapper about the article, the elevator thereafter beginning its upward movement to further fold the wrapper in cooperation with other wrapping instrumentalities.

25 Other objects and novel aspects of the invention relate to certain details of construction, arrangement of parts, timing and mode of operation of the mechanisms representing the preferred embodiment described hereinafter in view 30 of the annexed drawings, in which:

Fig. 1 is a perspective view of a wrapping machine looking toward the loading and initial wrapping mechanism;

35 Fig. 2 is a fragmentary top plan view of the loading and initial wrapping means viewed in the direction of line 2—2 of Fig. 1 and drawn to enlarged scale;

40 Fig. 3 is a fragmentary vertical section through the machine in the direction of line 3—3 of Fig. 2;

45 Fig. 4 is a transverse vertical section through the machine and loading table as viewed along line 4—4 of Fig. 3; while

50 Fig. 5 is a diagram of the driving cams.

While the improvements described and claimed herein are of general application in the art of wrapping machinery, they are illustrated in conjunction with a bread wrapping machine, and it is to be understood that reference herein to bread

wrapping is not to be construed as a limitation to the field of application of the improvements.

Generally speaking, the wrapping instrumentalities of the machine include a vertically reciprocable article carrier and horizontally reciprocable means for moving an article onto the carrier in its lowered position, together with means for feeding and positioning a sheet of wrapping paper so as to hang at one side of the article carrier in the path of the article transferred thereto, the wrapping paper or sheet being anchored at one end so that the remaining portions of the sheet are partly draped or folded about the article as the latter moves onto the carrier, the mechanisms being timed for cooperation so that as soon as the article has been moved against the wrapping paper and transferred onto the carrier, the latter will move upwardly and in doing so engage folding fingers and end folding members which effect additional folds, the upward movement of the article carrier being such that the fixed or anchored portions of the wrapper are additionally folded about the article until the carrier reaches its uppermost position, at which time the article is substantially wrapped save for outwardly projecting tails of the wrapper at opposite ends of the article, the article thereafter being automatically removed from the article carrier and passed between terminal end fold plates of improved construction which complete the folding and also cooperate in sealing the wrapper.

Referring to Fig. 1, the preferred embodiment of the machine includes a frame 10 mounted on strap means 12 at one side of the machine and adapted to receive an article such as a loaf of bread which is to be wrapped, such articles being placed on the table manually or fed thereto by suitable mechanism not shown herein. A loading table, generally indicated at 13, is mounted for reciprocation from a normal position alongside the receiving table 11 into and out of the machine opposite an article carrier or elevator 14 (Fig. 3) which is mounted at the upper end of a vertically reciprocable post 15, the elevator not being seen in Fig. 1 since it is in raised position. In Fig. 2, the loading table 13 is shown in its innermost position opposite the article platform of the elevator 14.

The loading table is mounted for reciprocable movement on a horizontally extending track in the form of a bar 18 secured to the frame structure 10 so as to extend transversely across the machine and beyond the one side thereof, the

platform portion of the table 13 consisting of two spaced plates 13a and 13b mounted on the horizontal web 19 of a casting which is disposed on the underside of the table, the casting having a 5 vertical web 20 on which are secured rollers 21 arranged to ride along the top and bottom portions of the track bar 18 (Figs. 3 and 4 particularly). The plates forming the platform or top of the loading table 13 are secured by any suitable means to the horizontal web 19 of the carriage or trolley casting, the web portion 19 of the latter having a transverse groove 22 formed therein (Fig. 4) which will be described hereinafter in conjunction with the article ejecting or transfer means.

Thus, the table is arranged for reciprocable movement on the track 18 from a position outside of the machine as viewed in Figs. 1 and 4, to a 20 position substantially within the machine opposite the elevator 14. Mechanism for reciprocating the loading table will be described in conjunction with the driving means for the elevator.

Means for engaging an article to hold the same in a proper or predetermined position on the loading table includes the provision of parallel arms 25 (Figs. 1 and 2), each mounted on angle brackets 26 and 26a and threadably movable toward and away from each other on a reversely threaded spindle 27 mounted as at 28 at the back side of 30 the top of the loading table and turned by means of an adjusting crank 29 to adjust the arms 25 to receive articles of different length.

The arms extend toward the receiving table 11, one of the arms 25 being yieldable to prevent injury to an article or loaf which may have been carelessly or improperly positioned on the loading table, one of the angle brackets or riders 26a being provided with a horizontal offset 30 on which an angle bracket 31 is pivoted as at 32 (Figs. 2 and 3) so that the arm 25' may pivot about the point 32 as a vertical axis from its normal position seen in Fig. 2, away from the companion arm 25, spring means 33 being arranged on a pintle 34 which extends through the riding bracket 26a and the 45 pivoted bracket 31 to which the arm is attached so that the latter is urged normally toward its companion arm into the position seen in Fig. 2.

Article ejecting or transferring means for the loading table includes the provision of a slide bar 35 (Figs. 2 and 3) which has parallel grooves on its opposite sides slidably interfitting with opposite edge portions 36 of the plates 13a and 13b which constitute the table or top portion 13 of the loading table. Thus, the slide bar is disposed 50 for horizontally sliding movement across the top of the loading table toward the receiving table 11 and elevator, this reciprocation being effected in 55 timed relation to the movements of the elevator and the loading table by means hereinafter to be described. A pusher member 38 is secured to one end of the slide bar 35 by having a horizontal tongue 39 thereon spot-welded to the bar 35 with the adjoining portions of the pusher 38 disposed 60 in a vertical plane beneath the guide arms 25. Thus, an article placed between the arms 25 against the pusher 38 when the latter is in its normal position, as viewed in Fig. 2, will be moved off of the loading table 13 toward and onto the 65 elevator 14 when the slide bar 35 is shifted toward the left.

The power plant of the machine includes a motor 40 (Figs. 3 and 4) which is drivingly connected through a speed reducer 41 and a sprocket chain 75 and gear drive 42-42' and a clutch 43 with a

main drive shaft 44 journaled in opposite sides of the frame 10.

Mounted on the shaft 44 (see also Fig. 5) are a pair of driving cams 45 and 46. A large bell crank 48 pivotally mounted as at 49 to float on a 5 cross shaft 50 beneath the main drive shaft, has a rider 51 which works in the cam track of cam 46, the opposite end of the crank being pivotally connected as at 52 with a link 53 drivingly connecting the same with the lower portion of the 10 elevator post 15 for reciprocation of the latter responsive to rotation of the cam 46.

Means for effecting reciprocation of the loading table 13 in timed relation with the movements of the elevator includes an irregularly shaped 15 crank lever 60 (Figs. 3 and 4) pivotally mounted as at 61 on a transverse member of the frame structure and having its upper end portion 62 pivotally connected with one end of a driving arm 63 which is pivotally connected as at 64 at its 20 opposite end with the vertical web 20 of the trolley or carriage casting. Thus, when the irregular crank 60 is rocked, the loading table is shifted back and forth on the track 18. Rocking of the lever 60 is accomplished through a connecting 25 rod 65 pivotally connected as at 66 to the lower end of the crank 60 and as at 67 to a stud 68 on the elevator bell crank lever 48 so that the elevator and loading table are reciprocated in timed relation by the cam 46, which for convenience may 30 be termed the elevator cam.

Means for actuating the ejecting mechanism or pusher 38 to remove an article from the loading table, includes a lever 70 (Figs. 3 and 4) pivotally mounted as at 71 at its lower end on a bracket 72 35 extended from the frame and having its upper end portion 70a disposed opposite the free end of the slide bar 35 which is attached to the pusher 38. The lever 70 has an arm 73 attached to its lower end for pivotal movement therewith, and 40 this arm is connected by a link 74 with a driving lever 75 which is keyed to the cross shaft 50. The cross shaft 50 is provided with a pair of transverse operating arms 76 (Figs. 1, 4, 5) keyed thereto for rocking movement therewith responsive 45 to the rotation of the transfer cam 45, one of the arms 76' having a cam follower 77 which rides in the cam track of the cam 45 (see Fig. 5 particularly), it being recalled that the bell crank 48 floats on the shaft 50 and therefore is rocked 50 independently of the rocking of the shaft 50 albeit in timed relation to the motion of the latter.

Thus, it will be observed in view of the diagram of Fig. 5 that each revolution of the main drive shaft 44 will effect a reciprocation of the transfer 55 arm 76 which in turn rocks the shaft 50 and effects a reciprocation of the ejector operating lever 70, and, in addition, the bell crank 48 is independently rocked to effect a reciprocation of the elevator, the foregoing movements occurring in a 60 certain timed relationship which will be explained in detail hereinafter.

It should be observed at this juncture that the driving connection between the lever 70 and the slide bar 35 for the ejector is impossible, with the 65 result that when the lever 70 is moved in one direction (left, Fig. 3), the slide bar 35 will be moved correspondingly to eject an article from the table. However, the lever 70, not being positively linked with the bar 35, the latter would 70 not be restored. In order to restore the ejector or pusher 38 to normal position in accurately timed relation to the restoration of the loading table to normal receiving position (the lever 70 being stationary relative to the movements of the 75

table), a stationary cam plate 78 is mounted at one (right-hand) side of the carriage track or trolley bar 18 so as to project a predetermined distance toward and beneath the loading table 5 when the latter is opposite the elevator, this cam plate having a slanted or cam edge 79 which is disposed to be engaged by a depending stud 79a on the slide rod 35 when the latter is moved inwardly of the loading table. When the loading 10 table is restored to initial position, the stud 79a bears against the cam edge 79 and shifts the slide rod 35 back to normal position (toward the right, Fig. 2), and the loading table is ready for another operation.

15 The loading means not only effects a transfer of an article onto the elevator at a proper instant of time in the wrapping cycle, but also effects an initial wrapping of the transferred article, and this is accomplished in cooperation 20 with automatic paper feed means which is more particularly described in the copending application of Gellman and Petskeyes, Serial No. 258,672. For present purposes, it is deemed sufficient to explain that a web of paper or analogous wrapping 25 material is fed from a supply roller 80 (Fig. 1) over a feeding roller 81 periodically rotated through a special driving connection with one of the transfer arms 76' and which connection is not seen especially illustrated herein but which is 30 described and claimed in the aforesaid copending application. The paper webbing is thus fed over the lower level 14' of the elevator 14 when the latter is in its raised position, and the free end of the web is automatically clamped on a 35 holding table generally indicated at 82 in Fig. 3 by a holding bail 83 which is actuated cooperatively with the elevator. Means (not shown in the present views) is also provided for severing the web to provide an opposite free end portion 40 which is moved downwardly with the elevator so that the sheet of wrapping material is suspended from its upper end in a substantially vertical plane, as indicated at 84 in Fig. 3, so as to lie across the path of an article moving from the 45 loading table 13 onto the upper level of the elevator 14.

A pair of initial wrapping and holding arms 50 85 is arranged to move up and down with the elevator in a position opposite the ends of the article or loaf, each of the arms 85 being attached to a vertically reciprocable slide rod 86 (Figs. 1, 2, and 3) mounted in sleeves, the lower end of each of the slide bars 86 resting on the top of the elevator in appropriate positions for the purpose 55 aforesaid.

The operation of the clutch means 43 is such that for every actuation thereof by means of a control handle 87 on the side of the frame (Fig. 1), the main drive shaft 44 will be rotated through one cycle or revolution, and the clutch will thereafter throw out automatically. Each revolution of the drive shaft 44 corresponds to a 60 complete wrapping cycle or operation, and the various mechanisms are arranged to come to rest 65 at the termination of each wrapping cycle with the loading table 13 positioned outwardly of the machine and opposite the receiving table 11, the elevator at this time being in raised position.

In wrapping operation, the attendant places an 70 article such as a loaf of bread on the receiving table 11 and guides the same in between the arms 25 on the loading table, any irregularity in the manipulation or size of the loaf (notwithstanding previous adjustment of arms 25 by 75 crank 29) being relieved by the yieldable mount-

ing 31-33 of the arm 25'. With the loaf thus positioned, the control handle 87 is raised and the elevator will descend to lowered position in timed relation with the inward movement of the loading table until the latter is positioned opposite the elevator as illustrated in Figs. 2 and 3, the elevator meanwhile having draped the wrapping paper 84 into position between the same and the loading table. Thereafter the pusher 38 is actuated through movement of the lever arm 70 to urge the loaf L toward the elevator and against the hanging wrapper 84, the loaf and wrapper being urged in between the arms 85 on the elevator with the result that initial end folds are effected through the agency of the arms 85, and 15 in addition the wrapper is folded over one side and a substantial portion of the top of the loaf with the lowermost end of the wrapper beneath the loaf. At this time the elevator starts upward and there is a further folding of the wrapper 20 around the top and the remaining side due to the fact that the upper end of the wrapper is held between the bail 83 and the table 82 (Fig. 3).

By the time the elevator or article carrying member has reached its fully raised position, 25 coacting mechanism (not shown herein, but described and claimed in the copending application of Petskeyes and Gellman, Serial No. 258,675) effects a release of the anchored wrapper, and transfer arms designated at 90 in Fig. 1 and 30 sliding on rails 91, are moved against the elevated loaf by connecting rods 92 attached to the transfer levers 76 and 76' for the purpose of removing the loaf from the elevator and urging the same into a terminal wrapping means consisting of 35 parallel end folding plates 93 and heating means for sealing the wrapper, at which time the wrapping cycle is complete and the various parts come to rest until the clutch control 87 is again operated, whereupon the foregoing cycle will be 40 repeated. Succeeding loaves push the leading loaves beyond the folding plates and onto a delivery table 94.

From the foregoing description, it will be apparent that the loading means 13-38 is an effective mechanism for coaction with an article carrier such as the elevator 14 for loading articles onto the latter in timed relation to the movements thereof, alone or in conjunction with other coacting instrumentalities. 45

Moreover, the loading mechanism 13-38 co-acting with the folding arms 85, alone or in conjunction with an article carrier such as the elevator 18, provides an effective initial wrapping means. There are thus two aspects of utility 50 55 characterizing the invention.

The objects and advantages of the invention in its various aspects may be realized by other forms of construction, arrangement and mode of operation of parts, than are described specifically herein for purposes of illustration, and the invention is therefore not to be limited to the precise form of the preferred embodiment except as may be provided in the appended claims.

Having thus described our invention, what we 65 claim as new and desire to protect by Letters Patent is:

1. In a wrapping machine of the type including a reciprocable article carrier and drive means therefor, loading mechanism including a table 70 arranged for reciprocation toward and away from said carrier in a particular reciprocal position, and means for engaging and moving an article on said table toward and onto said carrier when the latter is in said particular position, together with 75

- mechanism for reciprocating said table and actuating said article moving means in timed relation to the movement of said article carrier to effect transfer of articles from the table onto the carrier in the manner aforesaid.
2. In a wrapping machine of the type having a vertically reciprocable elevator, loading means including a substantially horizontally reciprocable loading table, ejecting means arranged for movement from a normal position to engage an article on said table and move the same in a direction off of the table toward said elevator, and drive mechanism coacting with said elevator, said loading table, and said ejecting means to effect movement of the loading table into position opposite said elevator when the latter is in substantially lowered position and subsequent actuation of said ejecting means, whereby to move an article from said table onto the elevator.
3. In a wrapping machine of the type having an article carrier arranged for reciprocation to effect wrapping operations on an article carried thereby, loading mechanism comprising a second article carrier arranged for back and forth movement toward and away from said first-mentioned article carrier when the latter is in a particular position, article ejecting means arranged for movement relative to an article on said second carrier to move said article off of said second carrier in a direction onto said first-mentioned carrier, and drive mechanism arranged for coaction with said carriers and said ejecting means to effect movement of said second-mentioned carrier into position opposite said first-mentioned carrier when the latter is in said particular position and further to effect actuation of said ejecting means to move an article from said second carrier onto said first carrier.
4. In a wrapping machine of the type having a vertically reciprocable elevator arranged for coaction in timed relation with wrapping instrumentalities to effect wrapping operations on an article carried by said elevator, loading means including a horizontally reciprocable loading table arranged for movement from a normal position into advanced position opposite the lowered position of said elevator, reciprocable article ejecting means on said loading table arranged for movement from a normal position to engage an article on said table and move the same toward and onto said elevator when said table is in advanced position, and drive means coacting with said wrapping instrumentalities, said elevator, said loading table, and said ejecting means for actuating the same in timed relation to effect movement of the loading table from normal position to advanced position opposite the lowered elevator and actuation of said ejecting means to eject an article from said table onto said elevator.
5. In a wrapping machine of the type having a vertically reciprocable wrapping elevator, a receiving table mounted in spaced relation to said elevator in a lowered position of the latter, a loading table mounted for reciprocation from a normal position alongside said receiving table to an advanced position alongside said elevator in the lowered position of the latter, ejecting means arranged for movement to engage an article on said loading table and move said article onto said elevator when the loading table is alongside the elevator, and drive mechanism arranged to effect reciprocation of said elevator and said loading table and actuation of said ejecting means in timed relation whereby said loading table will be moved from normal position alongside the receiving table into advanced position alongside the elevator and said ejecting means will be actuated to eject an article from the loading table onto the elevator.
6. In a wrapping machine of the type having a reciprocable article carrier arranged to effect wrapping operations on an article carried thereby in conjunction with other wrapping instrumentalities of the machine, automatic loading mechanism comprising: a loading carrier arranged for movement back and forth from a normal position to a position of alignment alongside said first-mentioned carrier when the latter is in a particular one of its reciprocal positions, and transfer means including a pusher arranged for reciprocation on said second-mentioned carrier to engage an article carried by the latter and move said article in a direction off of the second carrier onto the first carrier when the carriers are in aligned position as aforesaid, and drive means operably associating said carriers and arranged to effect reciprocation of said transfer means in timed relation whereby an article carried by said second carrier will be transferred onto said first carrier when the carriers are aligned in the manner aforesaid.
7. In a broad wrapping machine of the type having a vertically reciprocable elevator arranged for coaction in timed relation with associated wrapping instrumentalities, initial wrapping mechanism comprising a loading table arranged for horizontal reciprocation toward and away from a position of alignment opposite the elevator in a lowered position, a pusher arranged for reciprocation across said loading table to engage an article thereon and move the same off of the loading table onto the elevator when the table and elevator are aligned, means for positioning a wrapper across the path of an article moved from said table onto the elevator, and drive mechanism arranged to actuate said elevator, said table, said pusher, and said wrapper positioning means in timed relation whereby an article deposited on said loading table prior to movement of the latter into alignment with the elevator will be automatically moved off of the loading table into said wrapper and onto the elevator, and wrapping means coacting with said elevator to fold portions of said wrapper on said article.
8. In a bread wrapping machine of the type including a vertically reciprocable wrapping elevator arranged for timed coaction with paper feeding means adapted to suspend a wrapper at one side of the elevator during each cycle of movement thereof, a combination loading and initial wrapping mechanism comprising: a loading table mounted for horizontal reciprocation from a normal loaf-receiving position to aligned position alongside said elevator at a lower station of the latter, pusher means mounted for reciprocable movement from a normal position at one side of said table across the latter toward a wrapper suspended as aforesaid and said elevator to move an article from the table into the wrapper and onto the elevator, fold means on said elevator into which said article and wrapper are moved by said pusher means, and drive mechanism drivingly connected with said elevator, said paper feeding means, said loading table, and said pusher means whereby the loading table will be moved into alignment with the elevator in lowered position and said pusher means will be subsequently actuated to move an article into said wrapper and said wrapping means on the elevator to effect initial wrapping of the article prior to

movement of the elevator away from lowered position for additional wrapping movement of said articles.

9. In a device of the class described, loading means for coaction with a reciprocal article carrier, said means including a table arranged for reciprocation into and out of a position of alignment opposite said carrier when the latter is in a particular position, and transfer means arranged for movement in a direction across said table to engage an article thereon and move said article from the table in its position of alignment onto said carrier, together with driving mechanism drivingly connected with said carrier, said table, and said transfer means for reciprocating said carrier, moving said table into aligned position, and actuating said transfer means in the manner aforesaid.
10. In a device of the class described, article loading means for cooperation with a vertically reciprocable elevator, said loading means including a loading member arranged for movement back and forth in a horizontal direction into and out of a position of alignment opposite the elevator in its lowered position, pusher means mounted for movement with said loading member and arranged for movement from a normal position across said loading member to engage an article thereon and push said article from the loading member onto said elevator, drive mechanism operatively connected with said elevator and said loading member to move the same in timed relation into and out of aligned position, means coacting with said drive mechanism for operatively engaging said pusher means and moving the same out of normal position across said loading member to transfer an article as aforesaid substantially subsequent to the time said loading member is aligned with the elevator, and means for restoring said pusher means to normal position and including a stationary cam member positioned to be engaged by means cooperable with said pusher means to move the latter back to said normal position responsive to movement of said loading member out of aligned position relative to the elevator.

11. In a device of the class described, loading means for cooperation with a vertically recipro-

cable elevator, said means including a horizontally reciprocable table movable into and out of aligned position alongside said elevator in a particular position of the latter, pusher means on said table arranged for movement from a normal position to engage an article on the table and move said article onto the elevator when the table is in aligned position, and article holding means on said table and including spaced members one of which is arranged for movement toward and away from the other and provided with spring means normally urging the same toward said other spaced member, and drive mechanism operatively connected with said elevator, said table, and said pusher means to actuate the same in timed relation whereby an article positioned on the table prior to movement of the same into aligned position will be urged by said pusher means on to the elevator.

12. In a device of the class described, initial loading and wrapping means for cooperation with a vertically reciprocable wrapping elevator, said mechanism comprising: means cooperable with said elevator for positioning a wrapper in a substantially vertical plane alongside said elevator when the latter is in substantially lowered position, a loading table arranged for reciprocable movement into and out of aligned position alongside said elevator opposite said wrapper at the lowered position of the elevator, and transfer means including a transfer member arranged for actuation to engage and move an article into said wrapper from said table in aligned position and onto said elevator, spaced folding means arranged for movement with said elevator on the latter and between which an article and said wrapper are pressed by said transfer means, together with drive mechanism arranged to drive said elevator, said table, and said transfer means for effecting movement of the transfer means at a time when said table is moved into alignment with the elevator, said drive means further being arranged to actuate said wrapper positioning means to effect positioning of a wrapper as aforesaid for use when the elevator is in lowered position.
